COMBINED SERVICE SIGNAL LAMP AND ASH TRAY

William H. Middleton, 5606 Cheshire Lane, Houston, Tex.

Filed Aug. 13, 1964, Ser. No. 81,275

Term of patent 14 years

(Cl. D48—20)

FIGURE 1 is a top plan view of a combined service signal lamp and ash tray embodying my new design;

FIGURE 2 is a side elevational view thereof;

FIGURE 3 is an elevational view thereof as seen from the right side of FIGURE 2;

FIGURE 4 is an enlarged partial fragmentary sectional view as seen on the line 4—4 of FIGURE 2;

FIGURE 5 is a similar view as seen on the line 5—5 of FIGURE 3; and

FIGURE 6 is a perspective view thereof.

The dominant features of the design reside in the portions shown in full lines.

I claim:

The ornamental design for a combined service signal lamp and ash tray, as shown and described.
